UNITED STATES PATENT OFFICE.

JOHN H. KING, OF WATERVLIET, ASSIGNOR OF TWO-THIRDS TO FAYETTE B. DURANT, OF WEST TROY, AND HOWARD A. LANSING, OF MENANDS, NEW YORK.

DESIGN FOR A WASTE-WATER TRAP.

SPECIFICATION forming part of Design No. 24,350, dated May 28, 1895.

Application filed February 1, 1895. Serial No. 637,019. Term of patent 14 years.

To all whom it may concern:

Be it known that I, JOHN H. KING, a citizen of the United States, residing in the town of Watervliet, county of Albany, State of New York, have invented and produced a new and original Design for Waste-Water Traps, of which the following is a specification, reference being had to the accompanying drawings, forming a part thereof.

10 In the drawings, Figure 1 is a perspective view of a water-trap made in accordance with my design; and Fig. 2 is a sectional view of the same, taken on the line xx of Fig. 1. These two views are deemed sufficient to fully illustrate my design.

The leading feature of my design consists in a waste water trap in which there are four parallel pipes located at a short distance from each other, each pipe being at the corner of a substantial rectangle, when viewed in cross-section. Two of the pipes opposite each other are joined together at their ends and one end

of each of the other two pipes is joined to said communicating ends respectively.

Referring to the drawings, 1, 2, 3 and 4 indicate the four pipes respectively, two of which, 2 and 3 are joined together at their ends as shown at 5 and 6, and the ends of the pipes 1 and 4 are joined to said ends as shown at 7 and 8 respectively. When thus located it will be seen that the pipes 1 and 4 lie in a plane at right angles to the plane occupied by the pipes 2 and 3 and also occupy a position about midway between the lateral outside edges of said pipes when viewed from the front or rear.

What I claim as my invention, and desire to secure by Letters Patent, is—

The design for a waste water trap as herein shown and described.

JOHN H. KING.
